TIP-UP SEAT

James Mitchell, Glasgow, Scotland, assignor to
Mitchell, Russell and Company Limited, Stir-
lingshire, Scotland

Application April 5, 1933, Serial No. 664,512
In Great Britain December 28, 1932

6 Claims. (Cl. 155—85)

This invention relates to tip-up seats such as used in theatres and cinemas, and such as are adapted to be automatically tipped-up or require to have their tipping-up action manually initiated.

An object of the invention is to make such seats practically noiseless in action, without requiring the use of springs.

According to the invention, seat pivots located between front and rear abutments are each movable relatively to a guide during pivotal movement of the seat proper between its two limiting positions (namely, a "down" position and a tipped position), these positions being respectively defined by down-position and tipped-position rests around the former of which the initial portion of the tipping movement takes place, the remainder of the tipping movement taking place around the pivot while at one end of its guide.

20 In a preferred arrangement, the pivots consist of rollers which project sidewise from the seat proper, the guides being fixtures on the side-supports and being located immediately behind the previously mentioned down-position rest.

25 The arrangement is such that, when the seat proper is being tipped up, its centre of gravity is above the pivots and in or near the vertical plane containing them at the instant when they reach the end of their guides.

30 In the accompanying drawings:—

Fig. 1 is a sectional elevation of the seat.

Fig. 2 is a fragmentary section to a larger scale than Fig. 1.

Fig. 3 is a sectional plan view taken on the line III—III of Figs. 1 and 2, the view being to the same scale as Fig. 2 and showing the manner in which seat brackets are supported in the down position.

Fig. 4 is a fragmentary section on the line IV—IV of Fig. 2 and showing the construction of pivot and guide members.

Fig. 5 is a fragmentary section showing a modification.

The seat proper 4 is of the usual cushioned construction and is mounted on a pair of seat brackets 5 pivotally mounted, in a manner permitting the seat to tip up, between a pair of side-supports consisting of upright standards 6. In Fig. 2, the seat proper and one of its pivots are shown in full lines in the down position and in dotted lines in the tipped position. Numeral 7 indicates the usual back of the seat.

Each of the brackets 5 is secured to the under side of the seat proper by means of screws 8, and is provided with a laterally extending boss 9 pro-

vided with a projecting pivot pin 9a extending into a guide channel 10 which, as shown, may be formed integral with the standard 6. The guide channel 10 is of arcuate shape, being made to a radius from the point of contact between a buffer 5a and rest 13 hereinafter referred to, and it extends forwardly and downwardly and is of semi-circular shape at each end. It will be seen that the guide channel extends transverse to, or crosswise of the normal plane of the seat proper in down position, said plane being indicated by the line III—III in Figs. 1 and 2. A metal sleeve 11 is loosely fitted over the pivot pin 9a and carries in a circumferential groove therein a ring 12 of tough rubber, or vulcanite, or fibrous or like cushioning material, said ring constituting a roller.

Each of the two seat brackets 5 is provided on its under side with a pair of front and rear rubber buffers 5a and 5b, which function as abutments and the former of which rests, when the seat is occupied and the seat proper in the down position, on a front or down-position rest 13 which projects from the standard 6. The rear buffer 5b abuts against a bottom or tipped-position stop 14 when the seat proper is in the tipped position.

When the seat proper is in its down position, it is set, as shown in Fig. 1, at an inclination with its front higher than its rear, this setting being such that an occupant will naturally recline against the back 7, with the result that he will impart a forward thrust to the top of the seat proper. Moreover, the average occupant will as a rule bear upon the seat proper from the front thereof to about the part thereof vertically above the axis of the parts 12. It is found in practice that the resultant of the aforesaid forward thrust and the weight of the average occupant is directed in front of the front rests 13, and therefore the seat proper has no undesirable tendency to tip when properly occupied.

The location of the centre of gravity (which must not be confused with the centre) of the seat proper can be conveniently predetermined by appropriately dimensioning and distributing the weight of the brackets 5 in relation to the dimensions and weights of the other parts of the seat proper. In the construction shown, the bracket members 5 are for the most part disposed rearward of the front buffer 5a and they are sufficiently heavy to ensure that, when the seat proper is in the down position, a vertical line from its centre of gravity would extend downwardly between the pivot pin 9a and the buffer 5a, the seat

pivots being then at the upper end of the guide channels 10, as shown in full lines in Fig. 2. It will be evident, therefore, that the seat proper can only be held in the down position by some positive means such as the weight of the person occupying it, so that, immediately the occupier rises, the seat proper becomes out of balance and starts automatically to tip, the pivots sliding downwardly in the guide channels 10. This movement takes place about the point or place of contact between the buffer 5a and the rest 13, and continues until the pivot reaches the lower end of the guide channel. At this time, owing to the change in inclination of the seat proper, the unbalanced turning moment is considerably reduced, and the seat proper is nearly in equilibrium about the axis of the pivot pin 9a. Further, the movement of the seat proper about the point of contact between the buffer 5a and the rest 13 stops; nevertheless, the momentum of the seat carries it slowly to the fully tipped position, but the axis of rotation is now the pivot pin 9a. Finally, the seat proper comes to rest against the buffer 14.

Owing to this slowing up movement of the seat proper during tipping and to the provision of the cushion ring 12, as shown best in Fig. 4, the arrangement is practically noiseless. The cushion ring 12 rolls on the side of the guide channel and there is very little bumping; and, further, such wear as there is on the ring 12 is more or less uniform. The sleeve 11 and ring 12 can easily be removed and renewed.

It will be evident that the tipping-up action is dependent upon the distribution of weight of the seat proper and the relative positions of the pivots, guide channels, buffers 5a and the supporting rests 13. Therefore, the tipping up action may be increased or reduced as required by varying the distribution of weight and the relative positions.

Under another arrangement, which is not completely automatic, the weight of the seat proper is so disposed that a vertical line passing through the centre of gravity thereof would pass substantially through the point of contact between the buffer 5a and support 13, or even slightly in front of the point of contact. With this arrangement, the tipping action must be manually initiated, it being necessary to give the seat proper a slight lift at the front, and when this has been done, the pivot moves downwardly in the guide channel and the centre of gravity shifts to the rear of the point of contact, so that the tipping action is automatically continued.

Owing to the short distance that the pivot travels in the guide channel before coming to rest, it need not be a cushion ring, but may be instead a ring of harder material, such as metal. Instead of being formed integral with the standard 6 the sides of the guide channel 10 and the ledge 13 may be formed as one or more separate units which may be secured to the standard, for example, by screws.

It will be apparent that seats according to this invention are usually provided side-by-side in rows, although Figs. 1 to 4 show a seat consisting of a single independent unit. Where a seat is intended to form one of a row, each standard (except, if desired, the two end standards of the row) is adapted to support a seat at each side of it and is on this account formed or provided with a guide channel 10 at each side, as shown in Fig. 5.

In the construction illustrated, the pivot parts 9, 11, 12 project sidewise from the seat proper

and the guides 10 are provided on the supporting standards 6; but it will be obvious that the converse arrangement might be adopted, namely, the pivots might be provided on the standards and the guides on the seat proper.

I claim:—

1. A tip-up seat comprising a pair of spaced side-supports, front seat-rests on both side-supports, a seat proper arranged between said side-supports for movement between a down position 10 and a tipped position and including seat brackets, pivotal connections arranged behind said seat-rests and between said brackets and side-supports, said connections comprising channel guides, which are formed with semi-circular upper and lower closed ends and which extend behind said seat-rests arcuately thereto, and shock-absorbing rollers relatively movable from end-to-end of said guides, front buffers on said brackets, said buffers contacting with said rests 20 when the rollers are at one end of said channel guides and the seat proper is in the down position, rear buffer means on said brackets, and at least one stationary stop contacted by said rear buffer means when the rollers occupy the other 25 end of said guides and the seat proper is in the tipped position.

2. A tip-up seat comprising a pair of spaced side-supports, front seat-rests on both side-supports, channel guides thereon which are 30 formed with semi-circular upper and lower closed ends and which extend arcuately behind said seat-rests, a seat proper arranged between said side-supports for movement between a down position and a tipped position and provided 35 with seat brackets, shock-absorbing rollers which are journalled on said brackets and which are adapted to roll in engagement with said guides from end-to-end thereof, front buffers on said brackets, said buffers contacting with said rests 40 when the rollers are at one end of said channel guides and the seat proper is in the down position, rear buffer means on said brackets, and at least one stationary stop contacted by said rear buffer means when the rollers occupy the other 45 end of said guides and the seat proper is in the tipped position.

3. A tip-up seat comprising side-supports, front seat-rests on said side-supports, channel guides with closed upper and lower ends on said 50 side-supports, said guides being arranged behind said seat-rests and being arcuate thereto, a seat proper arranged between said side-supports for movement between a down position and a tipped position and including seat brackets, lateral projections on said brackets, shock-absorbing rollers on said projections, said rollers engaging and being movable from end-to-end of said channel guides, front buffers on said brackets, said buffers contacting with said rests 55 when the rollers are at the upper ends of said guides and the seat proper is in the down position, rear buffers on said brackets, and stops on said side-supports contacted by said rear buffers when the rollers are at the lower ends of said 60 guides and the seat proper is in the tipped position.

4. A tip-up seat comprising side-supports, a seat proper turnable between a down position and a tipped position, down-position and tipped-position stop means on said side-supports, front and rear abutments provided on said seat proper and adapted to abut against said down-position and tipped-position stop means respectively, the front abutment and down-position stop means 70

serving both as a support and a pivot for the seat proper in its down position, and inter-engaging side members which inter-connect the seat proper and side-supports and which are arranged 5 intermediate the front and rear abutments, said inter-engaging members comprising a guide and a pivot which moves relatively to the guide while the seat proper performs an initial turning movement around the front abutment and down-position stop means and which serves thereafter as the axis around which the seat proper tips upwardly towards the tipped-position stop while the pivot is at one end of said guide.

5. A tip-up seat comprising side-supports, 10 front seat-rests on the front of said side-supports, a seat proper arranged between said side-supports for movement in two stages between a down position and a tipped position, bracket means on said seat proper, down-position abutment means and tipped-position abutment means on said bracket means, pivotal connections between said bracket means and side-supports, said connection being arranged intermediate said down-position and tipped position abutment means and comprising relatively movable 15 channel guides and rollers, said guides being positioned rearwardly of the front seat rests and extending crosswise of the normal plane of the seat proper in the down position, and said front abutment means being adapted to contact with 20 said front seat-rests which serve as a pivot around which the seat proper performs the first stage of its tipping movement, during which

stage relative movement takes place between the rollers and their guides from end-to-end thereof, and stationary means contacted by said tipped-position abutment means on completion of the next stage of the tipping movement around the rollers at one end of their guides.

6. A tip-up seat comprising side-supports, front seat-rests on the front of said side-supports, a seat proper arranged between said side-supports for movement in two stages between a down position and a tipped position, bracket means on said seat proper, down-position abutment means and tipped-position abutment means on said bracket means, stationary channel guides arranged on said side supports and rearwardly of said front seat-rests, said guides extending crosswise of the normal plane of the seat proper in the down position, rollers which are journaled on said bracket means, are positioned between said down-position and tipped-position abutment means and are guided by said guides, said down-position abutment means being arranged to contact with said front seat-rests which serve as a pivot around which the seat proper performs the first stage of its tipping 25 movement, during which stage the rollers move from end-to-end of the guides, and stationary means contacted by said tipped-position abutment means on completion of the next stage of the tipping movement around the rollers at one 30 end of the guides.

JAMES MITCHELL.
